UNITED STATES PATENT OFFICE

ROBERT J. LEVY, OF NEW YORK, N. Y.

DESIGN FOR A KNIT SWEATER

Application filed November 10, 1932. Serial No. 45,866. Term of patent 3½ years.

To all whom it may concern:

Be it known that I, ROBERT J. LEVY, a citizen of the United States, residing at New York city, in the county of New York and State of New York, have invented a new, original, and ornamental Design for Knit Sweaters, of which the following is a specification, reference being had to the accompanying drawing, forming a part thereof.

I claim:—

The ornamental design for a knit sweater, as shown.

ROBERT J. LEVY.
